DENTAL RETAINER FOR MATRIX STRIPS

David Reiter, Woodside, N. Y.

Application July 12, 1950, Serial No. 173,259

16 Claims. (Cl. 32—63)

1

The present invention is directed to dental appliances, more particularly to a novel construction of a retainer for matrix strips or bands.

In making fillings for teeth, it is customary to remove the decayed portion and surround the tooth with a metal or plastic band and introduce the filling material into the space bounded by said band. For this purpose, it is necessary to supply means for holding the band in position and this has been accomplished by various appliances. Most of them include a number of screw threaded members and holding devices, whereby the ends of the strip or band are held in position with means for tightening the band to cause it to adhere closely to the teeth.

However, devices of this kind had numerous disadvantages and various difficulties arose in the use thereof. Because of the use of threaded members for anchoring the ends of the band, the latter became mutilated by the action of the locking screws. Also the ends of the bands usually extended at angles from the appliance so that the ends or edges thereof contacted with the gums or the cheek and caused injury thereof. There was also a difficulty in the dentist manipulating the device in that the elements were rather large and it was necessary for the dentist to rotate the threaded members by placing his fingers in the mouth of the patient. Even when the band was in place, it did not conform with the shape and irregularities of the various teeth so that leakage of the filling material took place during the packing thereof into the cavity so that shoulders were formed at the gum line which trapped food and caused decay to set in. Most of such devices were not only clumsy and difficult to adjust but were expensive and unsatisfactory in use.

The present invention is intended and adapted to overcome the difficulties and disadvantages inherent in devices of the type described, it being among the objects of the present invention to provide a retainer for matrix bands or strips, which is simple in construction and easy to manipulate.

It is also among the objects of the present invention to provide a retainer which allows automatic adjustment of the band by the mere tightening thereof regardless of the shape or size of the tooth being treated and without injury to the gum or cheek.

It is further among the objects of the present invention to provide a device of the character described, which allows a band to be locked in position without the necessity of using screws

2

for the purpose, which allows quick attachment thereof to the tooth and which may be readily removed without danger of injury to the filling or the mouth.

5 It is still further among the objects of the present invention to provide a device which in use is practically flush with the cheek, does not create any discomfort to the patient and which may be manipulated wholly or in part from the front of the mouth.

In practicing the present invention there is provided an elongated frame which has mounted in the rear portion thereof a spindle which may be propelled longitudinally of the frame. A band holder is provided on the front of the frame and is pivoted thereto. The holder has a transverse slot through which one or both of the free ends of a band may be threaded. A slide is provided which is capable of locking the band relative to the frame and the manipulation of the spindle is capable of tightening the band around the tooth. When this is done, the free ends of the band are substantially parallel to the frame and lie close thereto and since the frame is usually a flat bar or U-shaped member, it has no tendency to cut into the gum or cheek. As the spindle is rotated to tighten the band, the holder being pivoted will oscillate until the band as a whole has accommodated itself to the shape of the tooth. Molar teeth are usually narrower at the base than at the grinding surface but even in such a case the band adheres closely to the molar even at the base thereof.

35 In the accompanying drawing constituting a part hereof and in which like reference characters indicate like parts,

Fig. 1 is a side elevational view of a retainer for matrix strips or bands made in accordance with the present invention;

40 Fig. 2 is a view similar to Fig. 1, some parts being removed and some parts being broken away for clearness.

Fig. 3 is a side elevational view thereof taken from the opposite side of the retainer;

45 Fig. 4 is a transverse cross-sectional view thereof taken along line 4—4 of Fig. 1;

Fig. 5 is a fragmentary cross-sectional view of the front end of the device shown in Fig. 4, illustrating the position of a matrix band locked therein, ready for application;

Figs. 6 and 7 are opposite side views of a modified form of the invention;

Fig. 8 is a cross-section along line 8—8 of Fig. 6;

55 Fig. 9 is a fragmentary view similar to Fig. 6;

Fig. 10 is a cross-section along line 10—10 of Fig. 8;

Figs. 11 and 12 are opposite side views of a further modification of the invention, and

Fig. 13 is a cross-section along line 13—13 of Fig. 11.

Referring to the embodiment shown in Fig. 1, the frame consists of substantially parallel legs 1 and 2 joined together by a base 3. Leg 1 is somewhat longer than leg 2. Longitudinal slots 4 and 5 are provided in the central portions of legs 1 and 2, respectively and a transverse pivot 6 extends between the legs and is adapted to operate in the slots. A carriage 7 is secured to pivot 6 and a spindle 8 has its forward end mounted in carriage 7 to allow rotation of the spindle relative to the carriage. The rear of spindle 8 passes into block 9 which is mounted for rotation in base 3 and has a knob 10 at the rear thereof. The block is threaded as shown at 11 and serves as a means for retracting or propelling carriage 7 when knob 10 is rotated.

Within forward end 12 of leg 1 is mounted a holder plate 13 which is pivoted at 14 on pivot 6 and has a transverse slot 15 near its forward end. Tip 16 of holder 13 is tapered by a smooth curve so as to provide a minimum area at the tip thereof and thus avoid injury to the gum during the manipulation thereof.

On the outer face of leg 2 is a flat longitudinal slide 17 having the rear end 17' thereof turned upwardly to provide means for moving it. The slide has a longitudinal slot 18 through which pin 19 secured to forward end 2' of leg 2 extends. A second holder 20 lies over slide 17 having pin 19 passing through the rear portion thereof so as to allow oscillation of said pivoted holder about the pin. The forward end of holder 20 has a transverse slot therein and the tip 22 thereof is offset inwardly and is tapered to a small area. A guide pin 23 in portion 2' extends into arcuate slot 23' of holder 20 and serves as a means for limiting the arcuate travel of said holder. Front end 24 of slide 17 is adapted to pass through slot 21.

In utilizing the device knob 10 is manipulated so that slot 15 is forwardly of portion 12 as shown in Fig. 4. Slide 17 is retracted by pulling back on handle 17' until tip 24 thereof is free from slot 21 of holder 20. A matrix band is then introduced through slots 15 and 21 as shown in Fig. 5. Slide 17 is then pushed forwardly so that tip 24 frictionally engages the band and upon retraction of carriage 7 by rotation of knob 10, holder 13 is pulled back so that portion 12 frictionally engages the edges of slot 15 and holds the other end of the band in position. As shown in Fig. 5, end 25 of the band is practically parallel with frame 1 and provides a loop 26 which surrounds the tooth. The other end 27 of the band is also practically parallel to the frame. Then as knob 10 is rotated to further retract the carriage, portion 26 of the band is tightened about the tooth and when the tooth has an irregular shape, holder 20 oscillates about pivot 19, reducing the diameter of the band in accordance with the reduced diameter of the portion of the tooth to which it moves. Because of the rounded tip 22, there is no interference with the movement of the holder and it may freely assume its proper position automatically until the tension in all portions of the band is approximately equal. Because of this the band fits tightly around the tooth, regardless of its shape and the filing material may then be introduced without danger of any leakage.

When the filling is completed, slide 17 is retracted and end 27 of the band is then free to move. The retainer may then be slowly pulled from the mouth, causing end 27 to slip out of slot 21, and the band then slips out from around the tooth. In prior appliances, it was usually necessary to lift the band off of the tooth, in which case breakage of the edge of the filling was very likely to occur and this is eliminated by the present device. The manipulation for removal of the retainer may be accomplished in other manners, as for example, carriage 7 may be propelled to such a point that slot 15 is free and then the retainer may be pulled from the patient's mouth or both slots 15 and 21 may be freed and the retainer removed, after which the dentist may remove the band from the patient's tooth.

In the embodiment shown in Figs. 6 to 10 inclusive, there is provided a flat frame 30 having an angular end 31 and a longitudinal slot 32 in the central portion thereof. A pivot pin 33 passing through slot 32 is mounted on carriage 34 which carries threaded spindle 35. Said spindle passes through collar 36 which is mounted for rotation in an opening in end 31 and a knob 37 is secured to collar 36. Thereby rotation of the knob causes movement of carriage 34 relative to the frame. Slot 32 is provided with an enlarged opening 38 forming a keyhole slot.

The forward end of frame 30 is tapered and has a transverse slot 39 formed in said end. This may be provided by punching out a tongue 40 at right angles to the plane of frame 30. Tongue 40 and carriage 34 act as rest members to contact the teeth or gums and thus steady the retainer while being fitted and used.

Band holder 41 has a transverse slot 42 adapted to be aligned with slot 39 and it may be provided with an arcuate opening to accommodate a pin which would limit the lateral motion thereof. An opening 44 in the rear portion of holder 41 accommodates pin 33 so that the holder oscillates about the pin as a center. Head 45 on the free end of pin 33 holds the pin and carriage in position on the retainer. The diameter of head 45 is slightly less than that of opening 38 so that it may be inserted or removed in assembling or dismantling the retainer.

Slide 46 has an up-turned end 47 whereby it may be manipulated and adjacent thereto is a concave portion 48 adapted to seat in a similar portion 49 in the rear of frame 30, forming a latch to hold slide 46 in position. Said slide has a longitudinal slot 50 through which pin 33 passes and a circular opening 51 of sufficient diameter to accommodate head 45.

In the operation of the device knob 37 is rotated to propel carriage 34 forwardly until slots 39 and 42 are in alinement. A band is folded so that its ends 52 are in contact and it is slipped through slots 39 and 42, leaving a loop 53. Then knob 37 is rotated to retract carriage 34 and holder 41, causing the holder to slide under the end of slide 46 whereby the latter overlays slot 42 and causes ends 52 of the band to lie practically parallel to the frame. Loop 53 is then placed over the tooth to be treated and further retraction of carriage 34 causes tightening of the band around the tooth. At the same time holder 41 is free to oscillate and it will move so as to insure a tight fit of loop 53 around the tooth from top to bottom.

Referring to the modification shown in Figs. 11-13, there is provided a frame 55 which is flat and elongated, having an angular extension 56 at

the rear thereof. A rotating member 57 fits into an opening in extension 56 and a knob 58 is provided to enable one to rotate the same. A threaded spindle 59 passes through a similarly threaded opening in member 57 and is anchored in carriage or slide 60.

A screw 61 having a head 62 is threaded into carriage 60 and passes through longitudinal slot 63 in frame 55. Plate 64 is riveted to the rear end of frame 55 by rivet 65 and has a longitudinal slot 66 in alignment with slot 63, the screw 61 passing through slot 66. Washers 67 are provided on screw 61 at both sides of plate 64 to properly anchor the screw.

An oscillating band holder 68 interposed between frame 55 and plate 64 is pivoted on screw 61. The position of screw 61 may be changed to vary the distance between the frame and plate to accommodate bands of varying thickness.

A transverse slot 69 is provided in holder 68 and a complementary transverse slot 70 is formed in the forward end of frame 55 by punching a pair of tongues 71 out of said frame. The extreme end 72 of frame 55 is tapered so as to minimize interference with the placing of the retainer in position in the mouth.

A band of suitable material which may be of metal, plastic or the like, is doubled up. Carriage 60 is moved by rotation of knob 58 forwardly so that slots 69 and 70 are in register. Ends 73 of the band are inserted through the slots forming a loop 74. By manipulation of knob 58, carriage 60 is retracted, drawing holder 68 into a position whereby ends 73 are clamped between the holder and plate 64. Loop 74 is placed around the tooth to be treated and carriage 60 is further retracted until loop 74 has become tightened around the tooth. During this operation holder 68 oscillates and assumes a position wherein the band is tightened about the tooth regardless of its shape.

There are numerous advantages inherent in the invention, as for example, the retainer may be used not only for filling teeth but also for orthodontia, in which case the band may be tightened, leaving a folded line along which the band may be spot welded or soldered. When used for forming fillings, very little finishing of the filling is required and a denser filling is obtained.

The construction as a whole, including the tapered ends of several elements, insures that there will be no cutting of or injury to the gum, cheek or tongue of the patient. The band may be easily attached to the tooth by a simple manipulation of the knob and the ends of the band lay flat against the cheek or gum so as not to interfere with the dentist's operations. It is easy to manipulate because there is only one member that has to be operated. The device may be readily removed by movement of the spindle without any damage to the filling even though it may still be in a semi-soft condition. All widths of bands which are normally used by the dentist are adapted to be applied by a single retainer wherein the transverse slots are of sufficient width to accommodate the largest size of band.

The present retainer eliminates the cumbersome and complicated devices previously used which did not give an adequate fitting of the band on the tooth. The structure is simple, being mainly of flat elements close together so as to require very little space, giving the dentist a better opportunity of treating the tooth. The

tightening of the band is automatic due to the oscillating holder and there is no danger of filling material creeping under and out of the band.

The tongues are so located that they touch and engage the tooth and thus hold the retainer tightly even where a short tooth is being treated without danger of the band slipping off. In the embodiment of Figs. 11 to 13, the oscillating holder is free to move in accordance with the shape of the tooth as it does not press against the tooth but is held within the retainer. The screw 62 may be rotated in one direction or the other in order to adjust the space to accommodate various thicknesses of bands.

While the invention has been described setting forth several specific embodiments thereof, the invention is not to be limited thereto as the limitations were for the purpose of indicating the breadth and scope of the invention. Various changes in the details of construction may be made without departing from the principles herein set forth, as for example, the spindle may be of different character and may have coarse threads so that very little turning of the knob accomplishes the desired functions. An equivalent means may be substituted for the threaded arrangement shown and described. The form, size and arrangement of the parts may be specifically different from those shown and the materials of construction may be any of those suitable for the purpose. These and other changes may be made within the spirit of the invention, which is to be broadly construed and not to be limited except by the character of the claims appended hereto.

I claim:

1. A retainer for dental bands, comprising an elongated frame, a longitudinal propelling spindle mounted in said frame, means at one end of said frame for rotating said spindle, a band holder pivoted on said frame and having a transverse slot for said band near the free end thereof, a slide adapted to move longitudinally mounted on said frame, said slide being movable for frictional engagement with said slot to lock a band relative thereto, the other end of said spindle being operatively connected to said pivoted holder.

2. A retainer for dental bands, comprising an elongated frame, a longitudinal propelling spindle mounted in said frame, means at one end of said frame for rotating said spindle, a band holder pivoted on said frame and having a transverse slot for said band near the free end thereof, a slide adapted to move longitudinally mounted on said frame, said slide being movable for frictional engagement with said slot to lock a band relative thereto, the other end of said spindle being operatively connected to said pivoted holder, a second band holder secured at one end to said other end of said spindle and having a transverse slot for said band, said second holder adapted to be moved by said spindle to cause said frame to engage the edge of said slot to lock a band relative thereto.

3. A retainer for dental bands, comprising an elongated frame, a longitudinal propelling spindle mounted in said frame, means at one end of said frame for rotating said spindle, a band holder pivoted on said frame and having a transverse slot for said band near the free end thereof, a slide adapted to move longitudinally mounted on said frame, said slide being movable through said slot for frictional engagement with said slot to lock a band relative thereto, the other end of

said spindle being operatively connected to said pivoted holder.

4. A retainer for dental bands, comprising an elongated frame, a longitudinal propelling spindle mounted in said frame, means at one end of said frame for rotating said spindle, a band holder pivoted on said frame and having a transverse slot for said band near the free end thereof, a slide adapted to move longitudinally mounted on said frame, said slide being movable for frictional engagement with said slot to lock a band relative thereto, the other end of said spindle being operatively connected to said pivoted holder, a second band holder secured at one end to said other end of said spindle and having a transverse slot for said band, said second holder adapted to be moved by said spindle to cause said frame to engage the edge of said slot to lock a band relative thereto, said frame being U-shape, each of said holders being on a leg of said U.

5. A retainer for dental bands, comprising an elongated frame, a longitudinal propelling spindle mounted in said frame, means at one end of said frame for rotating said spindle, a band holder pivoted on said frame and having a transverse slot for said band near the free end thereof, a slide adapted to move longitudinally mounted on said frame, said slide being movable for frictional engagement with said slot to lock a band relative thereto, the other end of said spindle being operatively connected to said pivoted holder, a second band holder secured at one end to said other end of said spindle and having a transverse slot for said band, said second holder adapted to be moved by said spindle to cause said frame to engage the edge of said slot to lock a band relative thereto, said frame being U-shape, each of said holders being on a leg of said U and said rotating means being at the base thereof.

6. A retainer for dental bands, comprising an elongated frame, a longitudinal propelling spindle mounted in said frame, means at one end of said frame for rotating said spindle, a band holder pivoted on said frame and having a transverse slot for said band near the free end thereof, said frame having a transverse slot at the other end thereof adapted to be aligned with said holder slot, said spindle having its free end secured to the pivot of said holder, and means for frictionally engaging said slot to lock a band relative thereto.

7. A retainer for dental bands, comprising an elongated frame, a longitudinal propelling spindle mounted in said frame, means at one end of said frame for rotating said spindle, a band holder pivoted on said frame and having a transverse slot for said band near the free end thereof, said frame having a transverse slot at the other end thereof adapted to be aligned with said holder slot, said spindle having its free end secured to the pivot of said holder, and a slide mounted on said frame for frictionally engaging said slot to lock a band relative thereto.

8. A retainer for dental bands, comprising an elongated frame, a longitudinal propelling spindle mounted in said frame, means at one end of said frame for rotating said spindle, a band holder pivoted on said frame and having a transverse slot for said band near the free end thereof, said frame having a transverse slot at the other end thereof adapted to be aligned with said holder slot, said spindle having its free end secured to the pivot of said holder, and a slide mounted on said frame for frictionally engaging said slot to lock a band relative thereto and having a longitudinal slot through which said pivot passes.

9. A retainer for dental bands, comprising an elongated frame, a longitudinal propelling spindle mounted in said frame, means at one end of said frame for rotating said spindle, a band holder pivoted on said frame and having a transverse slot for said band near the free end thereof, said frame having a transverse slot at the other end thereof adapted to be aligned with said holder slot, said spindle having its free end secured to the pivot of said holder, and means for frictionally engaging said slot to lock a band relative thereto, said frame being flat, an angular extension at said first end, said spindle rotating means being mounted on said extension.

10. A retainer for dental bands, comprising an elongated frame, a longitudinal propelling spindle mounted in said frame, means at one end of said frame for rotating said spindle, a band holder pivoted on said frame and having a transverse slot for said band near the free end thereof, said frame having a transverse slot at the other end thereof adapted to be aligned with said holder slot, said spindle having its free end secured to the pivot of said holder, and a slide mounted on said frame for frictionally engaging said slot to lock a band relative thereto, said pivoted holder being located between said frame and slide.

11. A retainer for dental bands, comprising an elongated frame, a longitudinal propelling spindle mounted in said frame, means at one end for moving said spindle, a band holder pivoted on said frame and having a transverse slot for said band near the free end thereof, a slide mounted on said frame for movement relative to said holder to move over said slot, the other end of said spindle being operatively connected to said pivoted holder, whereby said holder may be moved relatively to said frame.

12. A retainer for dental bands, comprising an elongated frame, a longitudinal propelling spindle mounted in said frame, means at one end for moving said spindle, a band holder pivoted on said frame and having a transverse slot for said band near the free end thereof, the other end of said frame having a slot adapted to be aligned with said holder slot, a slide mounted on said frame for movement relative to said holder to move over said slot, the other end of said spindle being operatively connected to said pivoted holder, whereby said holder may be moved relatively to said frame.

13. A retainer for dental bands, comprising an elongated frame, a longitudinal propelling spindle mounted in said frame, means at one end for moving said spindle, a band holder pivoted on said frame and having a transverse slot for said band near the free end thereof, the other end of said frame having a slot adapted to be aligned with said holder slot, the edge of said frame slot having at least one upturned tongue, a slide mounted on said frame for movement relative to said holder to move over said slot, the other end of said spindle being operatively connected to said pivoted holder, whereby said holder may be moved relatively to said frame.

14. A retainer for dental bands, comprising an elongated frame, a longitudinal propelling spindle mounted in said frame, means at one end for moving said spindle, a band holder pivoted on said frame and having a transverse slot for said band near the free end thereof, a slide mounted on said frame for movement relative to said holder to move over said slot, the other end of said spindle being operatively connected to said pivoted holder, whereby said holder may be

moved relatively to said frame, said holder, frame and slide being substantially flat with said holder intermediate said other elements.

15. A retainer for dental bands, comprising a pair of elongated parallel members secured together at one end, a longitudinally movable spindle mounted on one of said members, a flat band holder between said members and being substantially in contact with both of said members, a carriage attached to said spindle, said 10 holder pivoted on said carriage, transverse slots in said holder and one of said members, whereby movement of said spindle in one direction folds and locks the ends of said band flat against said retainer and simultaneously tightens said band 15 around a tooth, while said pivoted holder oscillates to accommodate a tooth of any size or shape.

16. In a retainer for dental bands having a frame, a propelling spindle mounted therein, a 20

pair of band holders having transverse slots on said frame, one of said holders adapted to be shifted by movement of said spindle, the improvement which comprises a pair of tongues extending outwardly on opposite sides of one of said slots constituting means for minimizing interference by said retainer with placing the same in operative position.
